UNITED STATES PATENT OFFICE.

JOHN WARREN TEASDALE, OF ST. LOUIS, MISSOURI.

INTERNAL-COMBUSTION ENGINE.

Application filed August 26, 1926. Serial No. 131,571.

One object of my invention is to provide a multi-cylinder internal-combustion engine in which the flywheel is changed from the usual design, incorporated into the engine proper, and made to perform other functions in addition to the usual function of equalizing the speed of the crankshaft. The additional functions that this novel type of flywheel performs are regulating the admission of combustible gases into the cylinders, igniting these gases, regulating the exhausting of the burned gases from the cylinders, assisting in the circulation of the lubricating system, and performing other functions that will be hereinafter explained.

Another object of my invention is to provide a multi-cylinder engine in which the usual spark plugs and timers are not required, back-fires cannot occur, and the likelihood of pre-ignition taking place is practically eliminated. The usual valves and their operating mechanism are also eliminated, the flywheel performing their function for the entire engine.

Other objects of my invention are to provide an internal-combustion engine in which any degree of compression desired may be obtained without the use of superchargers or other exterior devices, in which an explosion in each cylinder with each revolution of the crankshaft is secured, and in which only one tapping or port in each cylinder is required, as the intake, exhaust and ignition are performed through the same opening.

Other objects of my invention are to provide an internal-combustion engine in which practically no expansion of the compressed gases occurs before the explosion thereof in spite of the fact that this explosion takes place after the pistons are well started on their movements away from the cylinder heads, in which the cylinders are completely scavenged by direct action of the pistons which expel the burnt gases from the cylinders before the fresh gases are introduced, and in which the full force of the explosions are transmitted to the crankshaft in such manner and at such time as to give it the greatest possible turning moment.

Still other objects of my invention are to provide a multi-cylinder engine in which the various parts are so compactly arranged that a minimum amount of space is occupied and the weight reduced by this arrangement

and by the elimination of numerous usually required parts. Other objects and desirable features will be hereinafter pointed out.

This invention is applicable to any number of cylinders, but since, as the number of cylinders are increased the other units comprising the engine are not proportionately increased in size and number, greater efficiency per cylinder is secured as their number is increased. For convenience and to illustrate the advantages to be derived from a multi-cylinder arrangement, I have shown on the accompanying drawings the application of my invention to a twelve cylinder engine composed of two groups of six cylinders each, radially disposed in a circular series about the crankshaft, with the sector-shaped spaces between the cylinders being utilized as compression chambers. One crank pin operates all the pistons of the cylinders of each group, and the crank arms of the two groups extend in opposite directions from the crank shaft, causing the corresponding cylinders in each group to be in exactly opposite phases. On the crank-shaft, between the two groups of cylinders, the flywheel is placed in such position that its flanges are in contact with a portion of the exterior of all of the cylinder heads, a portion of the curved surfaces of the compression chamber walls and with the circumferentially arranged gas supply, exhaust, and lubricating pipes. The flanges of this flywheel are also in contact with electrical contact brushes furnishing the current for the ignition of the charges in the cylinders. The invention consists in the flywheel and other parts, above set forth, and also in the internal-combustion engine and in the parts and combination and arrangement of parts.

In the accompanying drawings, wherein like reference characters indicate like parts, Figure 1 is a vertical section, taken in a plane perpendicular to the axis of the crankshaft.

Fig. 2 is a diagrammatic development of the periphery of the fly-wheel.

Fig. 3 is a detail showing the ignition device, taken on line III—III of Fig. 4.

Fig. 4 is a section taken along the line IV—IV of Fig. 1, perpendicular to it and on the same scale;

Fig. 5 is a similar section taken along the line V—V of Fig. 1;

Fig. 6 is a detail of one of the electrical contact brushes shown in Fig. 3.

Fig. 7 is a large scale detail of a portion of Fig. 4, showing a conductor band and friction strips in detail.

In the form of my invention shown on the accompanying drawings, A, B, C, D, E, and F designate cylinders radially disposed about a crank shaft 1 in Figure 1 about which the flywheel 3 rotates. Two crank arms 2 connect this crankshaft 1 with a crank pin 4, which, by means of connecting rods 6^a, 6^b, 6^c, 6^d, 6^e, and 6^f actuate piston heads 5^a, 5^b, 5^c, 5^d, 5^e, and 5^f. The connecting rod 6^a is fastened directly about the crank pin 4 where it is enlarged into a hollow distribution ring 7 to provide a connection for the other connecting rods. The connecting rods 6^b, 6^c, 6^d, 6^e, and 6^f are respectively connected to the distribution ring 7, by means of the pins 8^b, 8^c, 8^d, 8^e, and 8^f. The connecting rods 6^a, 6^b, 6^c, 6^d, 6^e, and 6^f are fastened in the usual manner to the piston heads 5^a, 5^b, 5^c, 5^d, 5^e, and 5^f, respectively by pins 9^a, 9^b, 9^c, 9^d, 9^e, and 9^f.

As the crankshaft revolves in a clock-wise direction, the various piston heads reciprocate in their cylinders in the usual manner, 5^a being one-sixth of a cycle behind 5^f and 30 equally much ahead of 5^b, 5^b being one-sixth of a complete cycle behind 5^a and ahead of 5^c, and so on. The corresponding cylinders of the other group are in opposite phase due to the crank arms 2' extending in the 35 opposite direction from the crank shaft 1 to that of the crank arms 2. Due to the indirect manner of the connection of all of the connecting rods except 6^a and 6^{a'} to the crank pins 4 and 4', the cycles of the various 40 pistons are not identical though nearly so. Their total movement in all cases is the same as is their period of reciprocation. This slight difference is not sufficient to require any adjustment in the timing of cylinder 45 valve functioning or ignition, but a slight adjustment is necessary for the devices operating the compression chambers, as explained hereinafter.

Piston head 5^a in Figure 1 is shown in its 50 position at the time of the explosion in cylinder D. It is already moving toward the crankshaft 1 and continues that motion for five-twelfths of a revolution of the crankshaft or until the crank pin 4 is at that 55 point in its orbit farthest from cylinder D and nearest to cylinder A and the piston head 5^a is at its maximum distance from its cylinder head. The exhaust is then opened and for one-half revolution of the 60 crankshaft the piston head 5^a moves in the direction away from the crankshaft until it almost, but not quite, touches its cylinder head, driving out the burnt gases and completely scavenging the cylinder. At this time the crank pin 4 is at the point of

its orbit nearest to cylinder D and farthest from cylinder A or eleven-twelfths of a revolution later than as shown in Figure 1. The exhaust is then closed and the piston head 5^a starts on its movement towards the 70 crankshaft 1. During the final one-twelfth revolution of the crank pin 4 to its position shown in Figure 1 and the movement of the piston head 5^a from almost touching its cylinder head to its position as shown in Figure 75 1, super-compressed gases are introduced into the cylinder and it is then again ready for the explosion. The cycles in all the cylinders of both groups are similar.

It will be noticed that in one revolution 80 of the crankshaft each cylinder goes through its complete cycle of explosion, exhaustion, and admission of pre-compressed gases for another explosion. It will also be noticed that at the time of the explosion in cylinder 85 D, as shown in Figure 1, the thrust of the connecting rod 6^a on the crank pin 4 as transmitted by the pin 8^a and the distribution ring 7 is almost tangential to the orbit 90 of the crank pin and in the line of its movement. Shortly thereafter it becomes so and thus is in the position to transmit the greatest possible turning moment to the crankshaft 1 at the time of its greatest thrust 95 which is at the time of the explosion and immediately thereafter, before the gases have had an opportunity to expand. The connecting rods of the other cylinders are in a similar position relative to their crank pins at the instant of explosion in their respective cylinders. 100

Compression chambers U, V, W, X, Y, and Z are sector shaped in cross section and fitted in between the cylinders. They are divided into compartments by their respective 105 diaphragms 10^u, 10^v, 10^w, 10^x, 10^y, and 10^z, which are pivoted at the apexes of the sectors by enlarged pins 11^u, 11^v, 11^w, 11^x, 11^y, and 11^z and swing through arcs of sixty degrees 110 from one radial boundary of the sectors to the other and back again, brushing the surfaces of the compression chambers. Around the periphery of each diaphragm, beginning at one end of the pin and terminating at the other, are flanges 100^u, 100^v, 100^w, 100^x, 100^y, 115 and 100^z, to give more surface in contact with the walls of the compression chambers and prevent the escape of gases from one compartment to the other.

At both ends of the compression chamber 120 pins 11^u, 11^v, 11^w, 11^x, 11^y, and 11^z, and rigidly fastened to them arms 12^u, 12^v, 12^w, 12^x, 12^y, and 12^z, extend in the opposite direction to that in which the diaphragms 125 extend. These arms are actuated by links 13^u, 13^v, 13^w, 13^x, 13^y, and 13^z, which are connected to them at their ends by pins 14^u, 14^v, 14^w, 14^x, 14^y, and 14^z. These links in turn 130 are actuated by the connecting rods and connected to them by pins through the shafts

of these connecting rods. Link 13^a is joined to connecting rod 6^a by a pin 15^a, 13^v to the connecting rod 6^b by a pin 15^b, 13^w to 6^c by 15^c, 13^x to 6^d by 15^d, 13^y to 6^e by 15^e, and 13^z to 6^f by 15^f.

The flanges 100^u, 100^v, 100^w, etc., of the diaphragms 10^u, 10^v, 10^w, etc., are reduced in width at the plane I—I where the section shown in Figure 1 is taken, as at this point, being on the axes of the cylinders A, B, C, etc., less depth is available for the recesses at the sides of the compression chambers into which the flanges of these diaphragms extend when in their extreme positions. This reduction of the flange width follows the curvature of the cylinders, dying out a short distance away from the axes of the cylinders on either side of these axes. The pins 11^u, 11^v, 11^w, etc., are enlarged so that gases cannot escape past them into the slots on the outside of the cylinder walls in which the diaphragm arms 12^u, 12^v, 12^w, etc., move.

As the connecting rods move back and forth in their respective cylinders, by means of the connections above mentioned, they cause the diaphragms in the adjacent compression chambers to oscillate back and forth. For instance, as the connecting rod 6^a moves toward the crankshaft 1 in Figure 1, it causes the link 13^x to force the arm 12^x to describe a sixty degree arc about the pin 11^x in the direction away from cylinder D and towards cylinder C. This in turn causes the diaphragm 10^x to move away from cylinder C towards cylinder D. As shown in Figure 1, the compartment of compression chamber X nearer cylinder C has been reduced to its minimum volume, having just given up its compressed gases to cylinder D. The compartment of compression chamber X nearer cylinder D is now filled with combustible gases at normal or atmospheric pressure which were admitted through a port 17^x which is now closed. As the diaphragm 10^x moves away from cylinder C towards cylinder D, combustible gases are sucked into the compartment of this compression chamber nearer cylinder C through a port 16^x.

When the diaphragm 10^x reaches a point almost over to the wall of cylinder D, the gases between this diaphragm and the wall of cylinder D will be highly compressed. At this point, the port 17^x is opened and remains open only until the diaphragm 10^x reaches the compression chamber wall next to cylinder D. The compressed gases between this diaphragm and this wall are forced through the port 17^x and pass into the cylinder B reinforcing those from compression chamber V which pass into this cylinder at the same time.

When the connecting rod 6^d starts on its motion away from the crankshaft 1, the link

13^x draws the arm 12^x back along the same arc path that it previously took, forcing the diaphragm 10^x away from cylinder D and towards cylinder C. During this movement the port 17^x is opened admitting fresh gases into the space between the wall of cylinder D and the diaphragm 10^x, and the port 16^x is closed so that the entrapped gases between the diaphragm 10^x and the wall of cylinder C are compressed. These compressed gases are passed to the cylinder D through the port 16^x when the diaphragm 10^x reaches a point nearly over to the cylinder C and after the piston head 5^d has started on its movement away from its cylinder head. At the same time, similarly compressed gases are also passed from the compression chamber Z to the cylinder D through a port 17^x. An instant before the piston head 5^d reaches the position shown in Figure 1, and as the diaphragms 10^x and 10^z reach the positions shown in this figure, the ports 17^x and 16^x are closed. The cycle is then completed and another cycle as above described is started.

A similar cycle is followed in each of the compression chambers to the end that each cylinder receives charges of compressed gases from two different compression chambers in each revolution of the crankshaft at the times these cylinders are ready to receive these charges. In the form of my invention here illustrated, the volume of the gases between each piston head and its cylinder head at the time of the explosion equals about one-twenty-fifth of the volume of the compression chamber compartments furnishing these gases. Compression in the cylinders will not be nearly so high as this ratio would indicate because of slight amounts of gas remaining in the compression chambers, gases remaining in the ducts connecting the compression chambers with the cylinders, and slight losses at the junction of these ducts with the ports of the compression chambers and those of the cylinders. The amount of compression in the cylinders may be increased or decreased by varying the size of the compression chambers. This can easily be done by extending or decreasing the depth of these compression chambers parallel to the length of the crankshaft.

If the links 13^u, 13^v, 13^w, 13^x, 13^y, and 13^z were connected to the piston heads 5^a, 5^b, 5^c, 5^d, 5^e, and 5^f, respectively, or to extensions from these, the maximum compression in one compartment of each compression chamber would occur when the piston head regulating it was nearest to its cylinder head and in the other compartment when this piston head was farthest from its cylinder head. At the time this maximum compression would occur, none of the cylinders in this group would be in the best period of their cycle to receive this compressed gas. The phase of the other group of cylinders might easily be

timed to receive these gases at maximum compression, but the compressed gases from their compression chambers in turn would be available when no cylinders were in the best position to receive such. Passing gases from the compression chambers of one group to the cylinders of the other may easily be done, however, in my invention, were that deemed desirable. By connecting the link 13^u to the piston head 5^b, a cycle similar to that of connecting it to the piston head 5^a would result with the phase of this cycle one-sixth of a revolution later, but the same disadvantages would ensue.

15 The method adopted for the form of my invention shown on the accompanying drawings, however, secures the maximum compression of the gases in both compartments of all compression chambers just at the time 20 nearby cylinders are ready for its reception. The path which the pin 15^a describes is not an ellipse, but it is symmetrical about a vertical axis which axis remains constant, regardless of the point it is placed on the connecting rod 6^a. The maximum lateral dimension of the path described by this pin varies with its position along the shaft of this connecting rod. By placing the pin 15^a at a certain point upon the connecting rod 30 6^a, this pin will describe such a path that a certain length line from any point on it will terminate at some point along the sixty degree arc that the pin 14^a describes and this line will terminate at one extremity of this 35 arc when the crank pin 4 is 180 degrees advanced from the position shown in Figure 1 and from the other extremity of this arc when this crank pin is 60 degrees advanced from the position shown. By placing the pin 15^a at a certain point on the connecting rod 6^a and by making the link 13^u a certain length, the pin 14^a, remaining always in its 40 60 degree arc, will be at one extremity of this arc when the piston head 5^a is in the position it assumes at the instant of explosion in the cylinder A and at the other extremity of this arc when the piston head 5^a is at the position it assumes at the instant of explosion in the cylinder E. Thus the 45 50 diaphragm 10^u is at one extreme position when the cylinder A is ready for the explosion and at the other extreme position when the cylinder E is ready for its explosion.

55 As the paths described by the pins 15^b, 15^c, 15^d, 15^e, and 15^f are not identical with that described by 15^a, due to the nature of the connection between the connecting rods 6^b, 6^c, 6^d, 6^e, and 6^f, through the distribution ring 7 to the crank pin 4, the exact position of 60 these pins upon these connecting rods must be determined in each case as well as the exact length of the links 13^v, 13^w, 13^x, 13^y, and 13^z, in order that the pins 14^v, 14^w, 14^x, 14^y, and 14^z will remain always in their 60 degree 65 arcs and reach the extremities of these arcs

at the time the cylinders which their respective compression chambers feed are ready for their explosion.

When thus properly determined, the pin 14^v and the diaphragm 10^v reach one extremity of their respective arcs as the piston head 5^b is in the position it assumes at the instant of explosion in cylinder B and the entrapped gases between this diaphragm and one wall of the compression chamber V are 70 conveyed to cylinder B. At the same time, the gases from compression chamber X are also conveyed to cylinder B. This pin and diaphragm reach the other extremity of their arcs when the piston head 5^c is in the position it assumes at the instant of explosion in cylinder F and the entrapped gases on the other side of this diaphragm 10^v are conveyed to cylinder F; at which time the gases from compression chamber Z are also conveyed to cylinder F. Pin 14^w and diaphragm 10^w are at their extreme points at the instants of explosion in cylinders C and A in like manner. Similarly diaphragm 10^x serves cylinders D and B; diaphragm 10^y serves cylinders E and C, and diaphragm 10^z serves cylinders F and D. As previously mentioned diaphragm 10^u serves cylinders A and E. The arrangement is similar in the other group of cylinders.

The compression chambers are connected to the cylinders which they feed for the period in which they are furnishing compressed gases to them. This period in every case starts as the piston head begins its motion away from its cylinder head and terminates just before the explosion. As the movement of the diaphragms in the compression chambers is so timed as to reach its extreme positions just as the communication between cylinder and compression chamber is terminated, practically no gas remains in that compartment of the compression chamber which is then at its minimum volume. If any considerable amount remained, when the diaphragm started on its return movement this would expand to normal volume before any new gases were sucked in, thus cutting down materially the efficiency of the compression. Just as the diaphragms reach their extreme points driving out the compressed gases, the compression chamber ports are closed and the ports in the cylinders through which these gases are admitted are also closed. Immediately thereafter the explosion takes place so that there is no opportunity for these gases to expand in the cylinders.

While the form of the compression chambers shown in the accompanying drawings, as well as the means used to operate them, is deemed desirable because of the peculiar advantages over other means of gaining super-compression, neither this form nor this method of functioning is essential to

the operation of the engine. Some of the advantages peculiar to this form and method are—great economy of space, economy of weight, ease of operation, great compression with high efficiency, lack of noise and minimum friction. Another advantage is that the lateral thrust of the piston heads on the sides of their cylinders is reduced as the links pivoted to the connecting rods at all times exert a force on these rods tending to counterbalance and offset this thrust. Another advantage is that no gears, eccentrics, slots, pawls, cams, springs, or other more or less objectionable devices, are required.

15 The flywheel 3, shown in cross-section in Figures 4 and 5, revolves with and about the crankshaft 1. Both inner and outer surfaces of the broad flanges of this wheel are in continuous contact with the various 20 portions of the engine forming its casing, thus covering and sealing the cylinder ports 18^a, 18^b, 18^c, etc., of one group of cylinders and 18^{a'}, 18^{b'}, 18^{c'}, etc., of the other group. These flanges also cover and seal all the 25 ports of the compression chambers 16^u, 16^v, etc., 17^u, 17^v, etc., as well as 16^{u'}, 17^{v'}, etc. On the outer flanges of the flywheel 3, directly opposite the cylinder ports 18^a, 18^b, 18^{a'}, 18^{b'}, etc., are exhaust ports 19^a, 19^b, 19^{a'}, 19^{b'}, etc. Extending through the 30 flanges of the flywheel 3 in the paths of these cylinder ports and exhaust ports are two exhaust slots 20 connecting temporarily the ports 18^a and 19^a, 18^b and 19^b, etc., and 20' serving a similar purpose for 18^{a'} and 19^{a'}, 18^{b'} and 19^{b'}, etc. As the flywheel 3 revolves, the slots 20 and 20', at the proper times, allow the exhaust gases to pass from the cylinder ports, through the exhaust ports and into two exhaust tubes 21 and 21' which 40 encircle the flywheel 3. An exhaust 22 connects to these two exhaust tubes and carries away the exhaust gases. A circular plate 23 containing these exhaust and other tubes is in two sections, bolted to the engine frame and to each other.

Also in the paths of the cylinder ports 18^a, 18^b, etc., on the inner side of the flange of the flywheel 3 is an intake slot 24 which 50 comes into register with these ports only during the time that the piston heads in the cylinders which they are then serving are moving from their cylinder heads to their position at the time the explosion takes place. An intake slot 24' serves a similar purpose for the cylinder ports 18^{a'}, 18^{b'}, etc. These intake slots 24 and 24' extend only part way through the flanges of the flywheel 3 and are connected by tubes 25 and 25' respectively to similar slots 26 and 26' on the inner sides of these flanges in the paths of the compression chamber ports 16^u, 16^v, etc., and 16^{u'}, 16^{v'}, etc. These slots 26 and 26' are in register with the ports of the compartments of the compression cham-

bers serving a cylinder at the same period that the intake slots 24 and 24' are in register with the cylinder ports of that cylinder so that the compressed gases flow from the compression chamber ports 16^u, 16^v, etc., 70 and 16^{u'}, 16^{v'}, etc., through slots 26 and 26', the tubes 25 and 25', the intake slots 24 and 24' and into the cylinder ports 18^a, 18^b, etc., and 18^{a'}, 18^{b'}, etc. Similarly two tubes 27 and 27' connect the slots 24 and 24' with slots 28 and 28'. These latter are similar in every way to the slots 26 and 26' except that they are located in the paths of the compression chamber ports 17^u, 17^v, etc., and 17^{u'}, 17^{v'}, etc., and serve these ports rather than 16^u, 16^v, etc., and 16^{u'}, 16^{v'}, etc.

Fresh explosive gases are admitted to the compression chambers through the compression chamber ports 16^u, 16^v, etc., and 16^{u'}, 16^{v'}, etc., by two supply slots 29 and 29' which extend through the flanges of the flywheel 3 and connect these ports with supply ports 30^u, 30^v, etc., and 30^{u'}, 30^{v'}, etc., in the circular plate 23 opposite their respective compression chamber ports. These supply slots 29 and 29' are in register with and connect these supply ports with these compression chamber ports at the time their respective compression chambers are in position to suck in these fresh gases. Similarly two supply slots 31 and 31' connect at the proper time the compression chamber ports 17^u, 17^v, etc., and 17^{u'}, 17^{v'}, etc., with their corresponding supply ports 30^u, 30^v, etc., and 30^{u'}, 30^{v'}, etc. These supply slots are bent in the thickness of the flywheel flange, as these supply ports and these compression chamber ports are not directly opposite one another. The same supply ports are served by both supply slots 29 and 31 as are the supply ports of the other group served by the supply slots 29' and 31'. The supply ports of each group are connected into their respective supply tubes 32 and 32' which encircle the circular plate 23 and are supplied by a supply pipe 33 leading from the carburetor or other source of supply.

The arrangement of the various slots and tubes in the flanges of the flywheel 3 is shown in the diagram Figure 3. It will be noticed that none of these slots interferes with any other slot and that all the various ports are connected with the proper duct at the proper time and only then and with no others. It will also be noticed that no valves of any sort, other than the flywheel, are required for the complete functioning which includes supply of fresh gases to each compartment of each compression chamber, conduction of these gases after compression from these compartments to the cylinders they serve, and removal of the burnt gases from the cylinders.

Due to the fact that the admission of the compressed gases into the cylinders is ter-

minated only an instant before the explosion takes place, these gases are, at the time of the explosion, in a state of rapid motion, thus producing a rapid and thorough combustion of these gases. The motion of these gases is more extensive and at a higher velocity than that caused by the various piston and cylinder shapes designed to produce turbulence in the usual types of internal-
10 combustion engines.

The compressed gases in the cylinders A, B, C, D, E, and F, are exploded by means of an igniting device 34 which is recessed into the inner side of the flange of the fly-
15 wheel 3 in such position as to come into register with each of the cylinder ports 18^a, 18^b, 18^c, etc., at the time it is desired to ignite these gases. This igniting device 34 consists of electrical insulating material in
20 which is a semi-spherical depression exposing a wire or bar of high electrical resistance 35. This wire makes contact with two screws 36 which are insulated conductors and which in turn make contact with insulated bar conductors 37 and serve to hold the igniting device 34 in place on the fly-
25 wheel 3. The bar conductors make separate contacts with insulated conductor bands 38 which encircle the periphery of the fly-
30 wheel 3. The cylinders A', B', C', etc., are similarly served by an igniting device 34', similarly constructed, and a high resistance wire 35' therein contained is similarly connected to the conductor bands 38 and 38'
35 by means of screws 36' and conductor bars 37'.

Figure 6 shows the method of supplying electrical current to these conductor bands 38 and 38', each band having a spring contact brush 39 and 39' respectively continually pressing against them. These two brushes are recessed into the circular plate 23, insulated, and connected by ordinary contact screws 51 and 51' to the wires furnishing the current. The current from these wires makes the two circuits as above indicated causing the high resistance wires 35 and 35' to be continuously incandescent. These incandescent surfaces coming in contact with the compressed gases in the cylinders when they pass the cylinder ports, ignite the same causing the explosion.

It will be noticed that no timing for the ignition system is required and no backfire
55 nor pre-ignition from mistiming can occur as the firing of each cylinder must take place when its piston head is in the proper position since this and the position of the firing device are both determined by the position
60 of the crankshaft. But two igniting devices are required for the twelve cylinders and they, being of simple construction, are much less susceptible to disorders than are spark plugs, of which twelve would be required
65 in the usual type of internal-combustion

engine. It will also be noticed that no backfire can occur because of the fact that the piston heads are already moving in their proper directions when the explosions take place, in fact from the time the compressed gases are admitted into the cylinders. Even if preignition were to occur, it would merely force the piston head in its proper direction. There is less likelihood of misfire in my invention than in other types of internal-com-
70 bustion engines for the reasons that the gases are so highly compressed and in such a state of turbulence as to insure combustion and the igniting device having a constantly in-
75 candescent surface, cannot fail to function or give a feeble spark as spark plugs might do.

To prevent the escape of gases about the various ports and slots on and opening onto the flanges of the fly wheel 3, and to provide an easily removed wearing surface for the areas in contact, friction bands are introduced, these being recessed either into the flanges of the flywheel or into the casing about the same. These friction bands serve a purpose similar to that of the piston rings of this engine or those of other types of internal-combustion engines. These friction bands are held in place by the spring or elasticity of the metal of which they are composed, being on the inner circumference of the two surfaces in contact and endeavoring to straighten out, thus keeping them against the outer circumference of these two surfaces. To prevent the escape of gases in the direction parallel to these bands and to make a gas-tight and easily removed wearing surface between these bands, they are arranged in groups or units and connected together by bars also recessed similarly to the friction bands.

Friction band units 40 and 40' consist of four friction bands each, joined together by friction bars 43 and 43' perpendicular to them. These entire units are recessed into the casing of the flywheel 3 and bear against the inner flanges of the flywheel, the spring of the metal of the bands keeping the entire unit in contact with these flanges. The bars of these units are placed at such points that they will not obstruct any of the ports to cylinders or compression chambers, but could be made so as to occupy all of the space in contact except these ports or as much of this space as desired.

Friction bank units 41 and 41' consist of three friction bands each joined together by friction bars 44 and 44'. These are all recessed into the outer flanges of the flywheel 3 and bear against the circular plate 23. The friction bars 44 and 44' are arranged about the circumference of the flywheel in such positions as to avoid crossing the slots or openings in the flanges of the flywheel. Friction band unit 42 consists of but two friction bands recessed into the flywheel on

either side of its axis. These bands are joined together by the friction bars 45 spaced about the circumference in such positions as to avoid all openings through this portion 5 of the flywheel 3. No friction bars cross the paths of the conductor bands 38 and 38'.

The flanges of the diaphragms 10^u, 10^v, etc., and 10^w, 10^x, etc., also have two friction bands each 46^u, 46^v, etc., and 46^w and 46^x, 10 etc. These extend around the periphery of their diaphragms from one end of the pins 11^u, 11^v, etc., and 11^w, 11^x, etc., to the other and serve a purpose similar to that of piston rings in combustion cylinders, bearing 15 against the walls of the compression chambers and preventing the escape of gases from one side of the diaphragm to the other.

Oil is supplied for the lubrication of the various parts of this engine through the 20 hollow crankshaft 1 and returned through an oil pipe 48 to an oil pump which again forces it back through the crankshaft in a continuous closed circuit. The route of this lubricating circuit for each group of cylinders is as follows: Crankshaft 1 to crank arms 2 which are hollow, to crankpin 4 which is also hollow, through holes 52 in the shell of the crank pin which extends through the inner shell of the distribution ring 7 to the hollow space of this connecting ring, 25 through small holes drilled through the centers of the pins 8^b, 8^c, 8^d, etc., which in each revolution of the crankshaft connect up twice with tubes 53^a, 53^b, 53^c, etc., in the connecting rods 6^b, 6^c, 6^d, etc., through these tubes to the pins 15^a, 15^b, 15^c, etc., through holes drilled through the centers of these which at each oscillation of the links 13^u, 13^v, 30 13^w, etc., connect with tubes 54^u, 54^v, 54^w, etc., in them, through these tubes to the pins 14^u, 14^v, 14^w, etc., through holes through these which at each forward and backward swing 35 of the arms 12^u, 12^v, 12^w, etc., connect with tubes 55^u, 55^v, 55^w, etc., in them, through these tubes to tubes 56^u, 56^v, 56^w, etc., running through the axes of the pins 11^u, 11^v, 11^w, etc., through these tubes and through holes 57 through the casing of the flywheel 40 3 which are prolongations of them to the space surrounding the flywheel, from this space through radial tubes 58 periodically spaced in the flywheel to an oil tube 47 which encircles the circular plate 23 and connects with the oil pipe 48 which returns to the oil pump.

Branches from this main circuit lead from the tubes 53^a, 53^b, 53^c, etc., and connect at each forward and backward movement of the piston heads 5^a, 5^b, 5^c, etc., to the piston pins 9^a, 9^b, 9^c, etc., through holes 59^a, 59^b, 59^c, etc., in the axis of these pins to the walls of the cylinders. Other branches lead from the radial tubes 58 in the flywheel 3 to ducts 60 in the flanges of the same that terminate 45 on the surface of the friction bands 40 in

minute openings. The friction bands 41 and 42 are similarly served by the ducts 61 and 62, through the circular plate 23 leading from the oil tube 47. The main crank bearings are served by holes 63 through the 70 crankshaft 1.

The friction bands 46^u, 46^v, 46^w, etc., are not served directly, but the surface of the flanges of the diaphragms 10^u, 10^v, 10^w, etc., between these bands are supplied by the 75 terminals of the tubes 56^u, 56^v, 56^w, etc., in the pins 11^u, 11^v, 11^w, etc., thus lubricating the surfaces of the compression chamber walls. Similarly the cylinder walls are served by the terminals of the tubes 59^a, 59^b, 59^c, etc., in the piston pins 9^a, 9^b, 9^c, etc. The lubricating circuits in the other groups of cylinders and compression chambers is similar.

Thus each pin and pivot, bearing and 85 wearing surface throughout the engine is supplied with lubricating oil. While the closed circulating system does not reach them all, lines leading from this system do, and with the oil at proper pressure adequate 90 lubrication of all points requiring it is secured. The ducts leading to the friction bands are small so that capillarity will assist the oil distribution. Capillarity also distributes the oil along the surfaces of the 95 friction bands, the walls of the cylinders and compression chambers and about the circumference of the various pins and pivots. The centrifugal force, due to the rapid rotation of the flywheel, materially assists the 100 oil circulation by increasing the velocity of the oil passing through the radial tubes 58 in the flywheel leading from the space surrounding it to the oil tube 47.

The engine is maintained at its most efficient temperature by a circulating water cooling system similar to those in general use. Cold water from a pump flows through inlets 49 and 49' and returns back to the cooling apparatus and pump through outlets 50 and 50'. The exterior surfaces of the cylinders are almost completely surrounded by the water of this cooling system and most of the exterior surfaces of the compression chambers are also exposed to it. 110 The spaces between the cylinders and compression chambers and the spaces encircling each group of cylinders and compression chambers are the passages through which 115 this cooling system circulates.

Since in Figures 1, and 4 the sections are taken on the axes of the cylinders, these drawings fail to give an adequate impression as to the extent of the volume of water within the engine and the amount of surface exposed to this water. In Figure 1 the metal between the cylinders and the adjoining compression chambers is a web connecting these at this plane to give rigidity and strength. This plane passes through the 120 125 130

- line of tangency between cylinder walls and compression chamber walls. In planes either in front or in rear of the plane on which this section is taken, a volume of 5 water is between each cylinder and compression chamber, which volume increases as the plane is taken farther from the axes of the cylinders. Similarly in Figure 4 the metal between the cylinders and the casing 10 rounding the flywheel is a web pierced with slots for the passage of the water. In planes either in front or in rear of the plane of this section a volume of water is between the cylinder and the flywheel casing.
- 15 No attempt has been made in the accompanying drawings to show parts or features characteristic of this type of internal-combustion engines except in so far as these parts or features are required to show the 20 functioning of this invention. For instance, the crank bearings are not shown, though ample space is allowed for them about the crankshaft. While each cylinder group is shown in two castings, each cylinder and 25 its adjoining compression chamber might be separate pieces or the cylinders and compression chambers might each be units.

What I claim is:

1. In an internal combustion engine, a flywheel of I shape in cross-section provided with passageways for gases in the broadened flanges thereof and adapted and arranged to control the passage of gases through the engine.
2. An internal combustion engine comprising a plurality of stationary cylinders arranged in a circular series, a crankshaft disposed axially of said cylinders, and a wheel with peripheral flanges secured to said 40 crankshaft and actuated directly thereby, said wheel being provided with passageways within said flanges adapted and arranged to coincide with openings in the cylinders at intervals to permit the escape of burnt gases from said cylinders.
3. An internal combustion engine comprising a plurality of stationary cylinders arranged in a circular series, a crankshaft disposed centrally of said cylinders and a wheel with peripheral flanges secured to said 50 crankshaft and actuated directly thereby, said wheel being provided with passageways within said flanges adapted and arranged to coincide with openings in said cylinders at intervals to permit the admission of combustible gases into said cylinders.
4. An internal combustion engine comprising a plurality of cylinders arranged in a circular series, a crankshaft disposed centrally of said cylinders, a plurality of compression chambers adapted to compress combustible gases and a wheel secured to said 60 crankshaft, said wheel being provided with passageways adapted at intervals to connect openings in said compression chambers with

the source of supply of combustible gases to permit the admission of said gases into said compression chambers.

5. An internal combustion engine comprising a plurality of cylinders arranged in 70 circular series, a plurality of compression chambers adapted to compress combustible gases for said cylinders, a crankshaft disposed centrally of said cylinders and a wheel on said crankshaft, said wheel being provided with passageways adapted and arranged to connect openings in said cylinders with openings in said compression chambers to permit passage of compressed gases from 75 said cylinders to said chambers. 80

6. An internal combustion engine comprising a plurality of stationary cylinders arranged in circular series, a crankshaft disposed centrally of said cylinders and a wheel secured to said crankshaft to rotate 85 directly therewith, said wheel being provided with passageways adapted and arranged to control the admission of combustible gases into the cylinders and the exhausting of burnt gases therefrom and provided with an igniting device for igniting 90 the charges in the several cylinders.

7. An internal combustion engine comprising a plurality of cylinders, an equal number of compression chambers for compressing combustible gases to be admitted to said cylinders and means for delivering compressed gases simultaneously from two compression chambers to a cylinder. 95

8. In an internal combustion engine a 100 plurality of compression chambers each provided with a pivoted diaphragm adapted to swing from one side to the other of its compression chamber.

9. In an internal combustion engine, a 105 plurality of compression chambers each provided with a diaphragm pivoted therein and adapted to swing from one side to the other of the chamber, said diaphragm being adapted and arranged to compress gases as it 110 moves in each direction.

10. In an internal combustion engine, a plurality of sector shaped compression chambers, each chamber being provided with a diaphragm pivoted at the apex thereof to 115 swing back and forth in said chamber, said diaphragm being adapted and arranged to compress the gases in the chamber in each direction of its travel.

11. In an internal combustion engine, a 120 plurality of alternating circularly disposed cylinders and compression chambers therefor, a crankshaft disposed centrally of said cylinders and compression chambers, diaphragms pivotally mounted in said chambers and actuating arms for said diaphragms connected thereto and to other moving parts 125 of the engine.

12. An internal combustion engine comprising a plurality of cylinders and compres- 130

sion chambers, said cylinders being provided with pistons and connecting rods, diaphragms pivotally mounted in said compression chambers and actuating arms for said diaphragms connected thereto and to said connecting rods of said pistons.

13. In an internal combustion engine in which a wheel is secured to the crankshaft to rotate therewith past a stationary member of the engine, a plurality of metal bands secured together to form a unit and interposed between said wheel and said stationary member, one of said members being grooved to receive said bands and the elasticity of the metal of said bands holding them in place.

14. In an internal combustion engine in which a wheel is secured to the crankshaft to rotate therewith past a stationary member

of the engine, a plurality of metal bands secured together by strips extending at angle 20 to said bands to form a unit and interposed between said wheel and said stationary member, one of said members being grooved to receive said bands and strips and the elasticity of the metal of said bands holding them 25 in place.

15. An internal combustion engine comprising a plurality of cylinders, a rotary fly-wheel, a casing for said fly-wheel, and a plurality of metal bands secured together to 30 form a unit and interposed between said fly-wheel and said casing, one of said members being grooved to receive said bands.

Signed at St. Louis, Missouri, this 24th day of August, 1926.

JOHN WARREN TEASDALE.
